COMBINED TOOTHBRUSH AND DENTAL FLOSS HOLDER

Leon A. Nowak, Milwaukee, Wis.

Application December 16, 1955, Serial No. 39,351

Term of patent 14 years

(Cl. D9—2)

FIG. 1

FIG. 2

FIG. 3

FIG. 4

FIG. 5

Figure 1 is a side elevational view of a combined toothbrush and dental floss holder embodying my new design;

Fig. 2 is a bottom plan view thereof;

Fig. 3 is an end elevational view taken from the left of Fig. 1;

Fig. 4 is an end elevational view taken from the right of Fig. 1;

Fig. 5 is a vertical transverse sectional view taken on the line 5—5 of Fig. 1; and

Fig. 6 is a vertical transverse sectional view taken on the line 6—6 of Fig. 1.

I claim:

The ornamental design for a combined toothbrush and dental floss holder, substantially as shown.
